UNITED STATES PATENT OFFICE.

FRANK E. TONIUTTI, OF FOREST PARK, ILLINOIS.

RAIN AND STORM COAT.

Application filed August 10, 1922. Serial No. 530,877.

To all whom it may concern:

Be it known that I, FRANK E. TONIUTTI, a citizen of the United States, and a resident of Forest Park, Cook County, and State 5 of Illinois, have invented certain new and useful Improvements in Rain and Storm Coats, of which the following is declared to be a full, clear, and exact description.

This invention relates to rain and storm 10 coats, and its principal object is to provide a garment of novel and improved construction for protecting the wearer against rain and snow. Another object is to provide a rain and storm proof garment adapted for 15 use by pedestrians, chauffeurs, and other drivers of vehicles, horse back riders, etc., and it is designed to protect the head, body, arms and legs of the wearer. Another object is to provide a garment of stylish and 20 attractive appearance, which may be readily converted into a practical and efficient rain and storm proof article of wearing apparel, for protecting the person of the wearer from rain, snow, etc. Another object is to provide 25 a stylish garment of neat and attractive appearance, with a hood or head covering, having the appearance (when not in use as a hood) of the usual conventional box plaits at the back of the coat, which may be readily 30 unfolded and brought over the head and head gear of the user. Other objects and advantages will appear in the course of the following specification, and with all of said objects and advantages in view, this invention 35 consists in the several novel features hereinafter set forth and claimed.

The invention is clearly illustrated in the accompanying drawings, in which:

Fig. 1 is a front elevation of a rain and 40 storm proof coat embodying a simple form of the present invention; Fig. 2 is a rear elevation, thereof; Fig. 3 is a front elevation of a fragment of the coat with the hood portion extended into position for usage; Fig. 45 4 is a rear elevation of the hood portion and a fragment of the coat proper; Fig. 5 is a detail vertical section taken on line 5—5 of Fig. 4; Fig. 6 is a rear elevation of the parts seen in Fig. 4 with the hood portion partly 50 distended; Fig. 7 is a detail cross section on line 7—7 of Fig. 4; Fig. 8 is a rear elevation of a fragment of the hood portion partly distended, and Fig. 9 is a perspective view of a fragment of the hood portion.

Referring to said drawings and first Figs. 1 and 2, the reference characters 20, 20,

designate the right and left tops or front portions of the garment, 21 the back portion, 22 the collar, 23 the lapels and 24 the sleeves of a coat embodying a simple form 60 of the present invention. These several parts may be cut and fashioned after the prevailing style, and of any desirable size and model. Preferably, a belt 25 is attached to the garment by seams or otherwise, which 65 belt may be worn outside of the garment or may be tucked in through the pockets and worn partly inside of the garment as is well understood. The coat and belt are buttoned or otherwise secured together at the 70 front as usual. Secured to the coat underneath the back portion of the collar 22 is a plaited portion 26, which extends down and terminates behind the belt 25, to which it is detachably secured by an ordinary snap 75 fastener 27. By reference to Fig. 2 it will be seen that the back 21 of the coat is formed with two, oppositely disposed plaits or folds 21^a, and that the plaited hood portion 26 completes the design of the back, giving 80 it the appearance of a box plaited back. Said hood portion 26, however, may be disconnected from the belt, and may be distended and drawn up over the head or hat of the wearer, as shown in Fig. 3, to thereby 85 protect the head and hat against rain. snow, etc.

The hood portion is of novel form and will now be described in detail. Referring to Figs. 3 to 9 inclusive, the material of the 90 hood portion is folded into "box plait" like folds running from top to bottom. It may comprise one piece of material, folded and stitched together as described. In Fig. 4, the dotted lines *a*, *b*, indicate the lines upon 95 which the folds are made, the intermediate parts *c* of the material, between the lines *a*, *b*, being laid on the central part *d*, between the lines *a*, *a*, and the outer parts *e*, being laid back on the parts *c*. The parts *c*, *e*, are cut 100 along the oblique lines *f*, *g*, and portions of the parts *e*, are rounded off at *h*; the end of the middle portion *d*, is also rounded off as at *i*. The oblique edges *f* are stitched to the middle part at *f*¹, and the oblique edges *g*, are 105 brought together and stitched together at *g*¹, and the round edges *h*, *i*, are stitched together. The edges *j*, are placed over and across and stitched to the middle part *d*. The end portion is folded up against the box 110 plaits (see Fig. 5) and fastened to the belt with the snap fastener 27. Along the un-

der edge portion are snap fastener members 28, and 29—29^a, and secured to the front of the coat, behind the lapels are straps 30 which have coacting snap fastener members 5 on their free ends, which are snapped upon any of the snap fastener members 28 to hold the front of the hood portion securely in place on the head or hat of the user (see Fig. 3). Loops 31 behind the lapels are provided, 10 through which the free ends of the straps 30 are passed when not in use. The lapels 23 conceal them when they are turned back (see Fig. 1.) The fasteners 29, 29^a co-act with each other, and are used to gather the 15 material together in giving shape to the hood. Other snap fasteners 32 are provided for holding the plaits *c* and *d* together. The snap fasteners 32 are concealed (see Fig. 4) when the hood is not distended. 20 The goods from which the garment is made comprises water proof material, and may comprise heavy or light weight water proof goods, or goods made water proof by processes well known to those skilled in the 25 art to which this invention pertains. While

the garment has the appearance of an ordinary coat it is readily convertible into a practical and efficient rain and storm proof garment.

More or less variation of the exact details of construction is possible without departing from the spirit of this invention; I desire, therefore, not to limit myself to the exact form of the construction shown and described, but intend, in the following claim, 35 to point out all of the invention disclosed herein.

I claim as new, and desire to secure by Letters Patent:

A garment comprising a coat portion having a belt, and a hood portion secured to said coat portion at the back, behind its collar, said hood portion having a lengthwise extending box plait, turned up at its lower end, with the plaited portion secured together at said upturned portion, the lower end of the hood portion being concealed behind said belt and detachably secured thereto. 40

FRANK E. TONIUTTI. 45
